ADVERTISING SIGN

Woodrow G. Terry, Salt Lake City, Utah, assignor to The Totem Pole Advertising Co., Salt Lake
City, Utah, a partnership

Application August 2, 1951, Serial No. 16,112

Term of patent 14 years

(Cl. D1—12)

To all whom it may concern:

Be it known that I, Woodrow G. Terry, a citizen of the United States, residing at Salt Lake City, in the State of Utah, have invented a new, original, and ornamental Design for an Advertising Sign, of which the following is a specification, reference being had to the accompanying drawing, forming a part hereof.

The figure is a perspective view of an advertising sign, showing my new design, in which the front and rear of the posts have the same general appearance.

I claim:

The ornamental design for an advertising sign, as shown and described.

WOODROW G. TERRY.
